UNITED STATES PATENT OFFICE.

GUIDO G. BEHN, OF DETROIT, MICHIGAN, AND ARTHUR E. COLMAN, OF AMESBURY, MASSACHUSETTS, ASSIGNORS OF ONE-HALF TO ESSEX MOTORS, OF DETROIT, MICHIGAN, A CORPORATION OF MICHIGAN, AND ONE-HALF TO THE BIDDLE & SMART COMPANY, OF AMESBURY, MASSACHUSETTS, A CORPORATION OF MASSACHUSETTS.

REMOVABLE PARTITION.

Application filed November 3, 1921. Serial No. 512,627.

To all whom it may concern:

Be it known that we, GUIDO G. BEHN and ARTHUR E. COLMAN, citizens of the United States, residing at Detroit, Wayne County, 5 State of Michigan, and at Amesbury, county of Essex, State of Massachusetts, respectively, have invented a certain new and useful Improvement in Removable Partitions, of which the following is a specification, reference being had therein to the accompanying drawings.

Our invention relates to a removable panel for closed bodies of automobiles and the like, and has for its object particularly 15 to provide means which will make it possible to renew a broken window pane or adjust or repair the window regulator with less labor than has heretofore been required. The invention has to do particularly with 20 the window pane located between the front and back compartments of closed cars such as "touring limousines" or "two-compartment sedans" in which there is a pane of glass slidable vertically in the back of the 25 front seat which makes it possible to transform the car from a one-compartment into a two-compartment car, or vice versa, by raising or lowering the pane.

Heretofore, as is well known to those 30 skilled in the art, a great objection to these bodies has been the fact that if the sliding pane between the front and rear compartments is broken, it has been necessary to remove the trimming on the back of the front 35 seat and adjacent parts and some of the woodwork to get out the pieces of broken glass and put the new pane in place. Similar work has also been necessary in case anything happens to the regulator or window lifter or to the guides in which the 40 panes slide. This work is not only objectionable on account of the delay and expense, but because it requires skilled workmen, and is likely to do permanent injury 45 to the interior trimmings of the body. Our invention makes it possible for a broken pane to be replaced, or a faulty regulator to be repaired or adjusted, by any ordinary mechanic who has no knowledge or skill of 50 upholstering, or by the owner of the vehicle, and the work can be done in a very short time. The work of replacing a pane, even though it should be done repeatedly,

does not do injury to the interior finish of the body.

The invention will be fully understood from the following description when taken in connection with the accompanying drawings, and the novel features thereof will be pointed out and clearly defined in the claims 55 at the close of this specification.

In the drawings, Fig. 1 is a view in perspective showing the location of the panel embodying our invention in the interior of a body of an automobile, the door of the 60 automobile being shown as open.

Fig. 2 is a rear view of a panel after it has been detached, the upholstery being removed to more clearly illustrate the construction.

Fig. 3 is a section on line 3 of Figure 2, showing also a portion of the body post and floor of the automobile.

Fig. 4 is a sectional view of the panel detached, the glass being shown in about the 75 lowest position.

Fig. 5 is a section on line 5 of Figure 2.

Referring now to the drawings, the pane of glass is shown at A and a removable panel at B (see Figure 1), this removable 80 panel being shown in detail and on a larger scale in Figures 2 to 5 inclusive. The removable panel B is held in place by screws C, the heads of which rest on large washers D which themselves bear against the trimming material with which the body is lined.

The removable panel consists of a frame made up of two horizontal members 11 and 12, two vertical members 13 and 14, and braces 15, the whole being secured together 85 in any suitable manner as, for instance, by wood screws 16. On the front face of the panel are secured two vertical guides 17 and 18 in which the edge of the glass A is guided. These guides are preferably U-shaped metal channels of the ordinary construction, and they terminate at their upper ends at the level of the upper edge of the panel, as shown in Figures 2 and 4.

Above the upper ends of the channels 17 100 and 18 and secured to the post 19 of the body, are two other guides, one of which, 21, is shown in Figure 3. These guides are secured permanently in place and are in line with the guides 17 and 18 respectively, 105 so that the glass as it is raised, runs in

both channels except when it is in its lowest position.

The lower edge of the pane A rests in a horizontal channel member 22 to which is secured a slotted lug 3 for the reception of the pin 4 which is secured to one link 5 of the regulator chain 6. The regulator employed may be of any convenient type, such devices being obtainable in the open market. In the drawings, we have shown a chain regulator provided with two sprocket wheels 7 and 8 with a crank handle 30 on a shaft 9 projecting rearwardly through the panel into the rear compartment of the body. The upper sprocket wheel 8 is mounted on a plate 31 secured to the upper member 12 of the removable panel B, and the lower sprocket wheel is similarly secured to the lower member 11. It will, therefore, be seen that the rotation of the handle 30 lifts or lowers the pane A vertically, the pin 4 being free to slide in the slot in the lug 3 to allow for any variation from the vertical in the path of the pin 4.

The back of the frame of the removable panel is closed by a metal sheet 32, and the rear surface may be finished in any desired manner, preferably to conform to the trimming of the remainder of the rear compartment. In ordinary practice, stuffing of curled hair, as shown at 33, is applied and this in turn is covered with a lining (not shown) and some upholstery material such as broadcloth or corduroy, this being designated 34 in the drawings. The cloth and stuffing are tacked or properly secured to the panel, and the whole forms a removable unitary structure, on the front face of which are the regulator and pane of glass while on the back face are the upholstery and regulator handle. The panel is secured in place in the back of the front seat by the screws C, as already described.

While we have described our removable panel in the form in which it is constructed for use on the back of the front seat of a vehicle body which is convertible from one compartment into two, the use of our removable panel is not limited to that position, since we contemplate its use in doors and other places in the vehicle. We have, however, described it in the position shown in the drawings, since that is the manner in which we have already put our invention into practical use.

In case the pane of glass is broken, the regulator and pane are lowered far enough to free the upper edge of the pane from the fixed guides 21, then the screws C are removed and the panel is taken out. This exposes the regulator to view and the broken glass may be removed from the channels and the pocket. The new pane of glass is then placed in the horizontal chan-

nel member 22, this being in its lowest position, and the removable panel is put back and secured in place by reinserting the screws C. The work of replacing the panel, as will be seen, does not involve any change whatever in the upholstery, and can be done without the slightest injury even to the most delicate fabric.

What I claim is:

1. In an automobile body, a removable unit comprising a panel having a window regulator and guides for a sliding pane mounted thereon, and means for securing said unit as a whole detachably in place in the body. 80

2. In an automobile body, a removable unit comprising a panel having on one face a window regulator secured thereto and having the other face finished to correspond with the finish of the interior of the body, 85 and means for detachably securing said unit as a whole in place in the body.

3. In an automobile body, a removable unit comprising a panel forming the back of the front seat, the front of said panel 90 being provided with a window regulator, and the back of the panel being finished to correspond with the finish of the interior of the rear compartment of the body, and means for detachably securing said unit as 95 a whole to said seat.

4. In an automobile body, a removable unit forming the back of the front seat, said unit comprising a panel, a sliding pane carried by said panel and forming with the 100 front seat a partition between the compartments of the body, a window regulator for said pane secured to the front of the panel, and upholstery permanently attached to the back of the panel, and means for detachably securing said unit as a whole to said seat.

5. In an automobile body, a removable unit forming the back of the front seat, said unit comprising a panel, a sliding pane to form with the front seat a partition between the front and rear compartments, guides for the pane, a window regulator secured to the front of the panel and upholstery on the back of the panel, and means for detachably securing said unit as a whole 110 to said front seat.

6. In an automobile body, a removable unit comprising a panel having on one face a window regulator secured thereto and having the other face finished to correspond with the finish of the interior of the body, the handle of the regulator extending through the said panel and being on the side opposite the regulator, and means for detachably securing said unit as a whole in 120 place in said body.

7. In an automobile body, fixed guides for a movable window pane extending to a point about midway of the travel of the pane, a removable unit comprising a panel 130

- itself provided with guides and located below the fixed guides so that the guides on the panel are in line with the fixed guides, a window regulator on one face of the said panel, the other face of the panel being finished to correspond with the interior of the body, and means for detachably securing said unit as a whole in place in said body.
- 10 8. In an automobile body, a removable unit comprising a panel, a window regulator

and guides for a window pane mounted on said panel, the handle of the regulator extending through the panel and being on the side opposite the regulator, and means for detachably securing said unit as a whole in place in the body.

In testimony whereof we affix our signatures.

GUIDO G. BEHN.
ARTHUR E. COLMA
